UNITED STATES PATENT OFFICE.

HENRY BARKSCHAT, OF LOS ANGELES, CALIFORNIA, ASSIGNOR TO MARBELITE CORPORATION OF AMERICA, OF LOS ANGELES, CALIFORNIA, A CORPORATION OF DELAWARE.

DESIGN FOR A LIGHTING-STANDARD CAPITAL.

Application filed February 6, 1926. Serial No. 16,425. Term of patent 14 years.

To all whom it may concern:

Be it known that I, HENRY BARKSCHAT, a citizen of the United States, residing at Los Angeles, in the county of Los Angeles, State of California, have invented a new, original, and ornamental Design for a Lighting-Standard Capital, of which the following is a specification, reference being had to the accompanying drawing, forming a part thereof.

The figure is an elevation of a lighting standard capital showing my new design; the design being substantially the same on the opposite side from that shown.

I claim:

The ornamental design for a lighting standard capital as shown.

HENRY BARKSCHAT.
